UNITED STATES PATENT OFFICE.

ALBERT G. ROCKFELLOW, OF ASHLAND, OREGON.

GATE-LATCH.

SPECIFICATION forming part of Letters Patent No. 311,787, dated February 3, 1885.

Application filed April 8, 1884. (No model.)

To all whom it may concern:

Be it known that I, ALBERT G. ROCKFELLOW, a citizen of the United States, residing at Ashland, in the county of Jackson and State 5 of Oregon, have invented certain new and useful Improvements in Gate-Latches, of which the following is a description.

Figure 1 is a front elevation of a gate embodying my improvement hinged to a fence-post. Figs. 2 and 3 are side and front views, respectively, of the catch. Fig. 4 is an edge view of the latch. Fig. 5 is a side view of the same. Fig. 6 is a longitudinal central view of the same, with one-half of the casing removed; 15 and Fig. 7 is a transverse section of the casing in the line $\alpha\alpha$ of Fig. 5.

My invention relates to improvements in gate-latches for which Letters Patent were granted to me, dated March 26, 1878, No. 20 201,703, and reissued December 10, 1878, No. 8,515; and it consists in the peculiar construction and arrangement of the parts, as herein-after more fully set forth, and pointed out in the claims.

25 A represents the post on which the gate C is hung, and B the post against which it closes. The gate may be either a picket, door-panel, or other form of gate. The gate C is hinged to the post A by the hinges e , of peculiar construction, which hinges, however, form no part of the present application.

30 h' represents a latch-case, mortised into the upright E of the gate C, opposite the catch m , secured to the post B. The upright E of the gate is provided with a central mortise, for the reception of the latch-case h' and a transverse bolt-hole, h^2 . The latch-case h' is provided with two horizontal flanges, h^3 , provided with screw-holes, whereby the latch-case is secured to the upright E. The latch-case h' is also provided at its upper end with two opposite slots, h^4 , provided at their lower ends with horizontal flanges h^5 , having a semicircular opening, h^6 , in each, in which rests the pointed lower end of a bolt, h^7 , secured at its upper end to a rectangular latch or bolt, h^8 , adapted to slide back and forth in the latch-case h' .

35 h^9 represents a spiral spring coiled around the bolt h^7 , one end (the lower) resting against the horizontal flanges h^5 , and the upper end of the spiral spring h^9 bearing against a disk, h^{10} , secured to the under face of the rectangular bolt h^8 , the tension of the spring h^9 being 40 always exerted to force the rectangular latch

or bolt h^8 outward. The side arms, h^{11} , of the rectangular bolt or latch h^8 are hooked at their lower ends at h^{12} , to engage with a tumbler, n , having a square bolt-hole in line with a hole in the latch-case and the transverse bolt-hole h^2 in the upright E, whereby the latch h^8 is operated by a knob on said bolt. o represents the shank of the catch m , threaded at one end, and adapted to be inserted to any depth desired in the post B. The threaded shank o is 45 provided with a circular head, F, which consists of the two opposite inclined planes o' , provided with a central notch or groove, P, and the transverse notches p of each end of the groove P, and secondary notches or offsets 50 Q at each side of the center notch, so that if the closing force should carry the latch-bolt h^8 beyond the main notch P it will be caught by the secondary notch Q and thrown back into the main notch P. This construction of 55 catch forms the subject-matter of a claim in my Reissue No. 8,515, dated December 10, 1878, and the present construction of catch differs from that construction in providing a circular head and the upper and lower ends 60 of the main notch or groove P with notches p p , for a vertically-working latch to catch into.

Having thus fully described my invention, what I claim as new, and desire to secure by Letters Patent, is—

85

1. An adjustable catch for latches, consisting of a threaded bolt or shank, o , double inclined circular head F, having central groove or notch, P, provided with end notches, p p , and secondary notches or offsets Q, substantially as specified, whereby the catch is adapted to catch and hold a vertically or horizontally moving latch, as set forth.

90

2. The combination, with the slotted latch-case h' , provided with flanges h^5 , of the bolt h^8 , spring h^9 , rectangular bolt h^8 , hooked at its lower ends, and tumbler n , substantially as shown and described.

95

3. The combination, with an adjustable catch for latches, consisting of a threaded bolt, o , double inclined head F, having central notch, P, with end or transverse notches, p p , and secondary notches Q, of the slotted latch-case h' , provided with flanges h^5 , bolt h^7 , spring h^9 , rectangular bolt h^8 , hooked at its lower end, and tumbler n , substantially as shown and described.
